UNITED STATES PATENT OFFICE.

FREDERICK L. WILLARD, OF NEW YORK, N. Y., ASSIGNOR OF ONE-HALF TO
GEORGE WEIDERMAN, OF NEW YORK, N. Y.

CIRCUIT MAKING AND BREAKING DEVICE.

No. 847,299.

Specification of Letters Patent.

Patented March 12, 1907.

Original application filed October 2, 1905, Serial No. 280,928. Divided and this application filed February 14, 1906.
Serial No. 301,033.

To all whom it may concern:

Be it known that I, FREDERICK L. WILLARD, a subject of the King of Great Britain, and residing at New York, in the county of 5 New York and State of New York, have invented certain new and useful Improvements in Circuit Making and Breaking Devices, of which the following is a specification, such as will enable those skilled in the art to which it 10 appertains to make and use the same.

The object of my invention is to provide a magnetically-operating switch with attached circuit-breaker designed to be used in connection with electrical operating devices— 15 such as controllers for electric motors, elevators, electrical sign-displays and the like—and a further object being to provide a magnetic circuit-breaker in which the magnet is called upon to exert but very little power in 20 order to accomplish the object for which it is designed by a minimum expenditure of electrical energy; and with these and other objects in view the invention consists in a device constructed as hereinafter described and 25 claimed.

This application is a division of another application, filed by me October 2, 1905, Serial No. 280,928; and the invention, as described and claimed herein, is fully disclosed 30 in the following specification, of which the accompanying drawing forms a part, in which the separate parts of my improvement are designated by suitable reference characters in each of the views, and in which—

35 Figure 1 is a front elevation of a series of such circuit-breakers, as preferably arranged in connection with a controlling device for electric elevators or other apparatus of such nature; Fig. 2, a side elevation of my invention; Fig. 3, a partial section on the line 3 3 of Fig. 1; and Fig. 4, a diagrammatic view of 40 a controlling device in which my magnetic circuit-breaker is employed.

In the drawing forming part of this specification I have shown a plate *a*, preferably composed of slate or other non-conducting material, upon which is placed a casing *a*² and upon the outer face of which is mounted a base-plate *a*³, also composed of slate or 45 other non-conducting material, and within the casing *a*², although not shown in the drawings, suitable electrical devices—such as resistances, solenoid, &c.—can be located.

Pivottally mounted on the base *a*³ are the magnetic circuit-breakers *a*⁴, four of which are shown in front elevation in Fig. 1 and one of which is shown in side elevation in Fig. 2. This device consists of a supporting-frame *b*, having at its lower end two projecting lugs *b*¹, between which is pivotally connected an armature *b*². This support *b* has at its lower end a projecting block *b*³, and the lower end of the armature *b*² has also a projecting extension *b*⁴, which is provided with an adjustable set-screw *b*⁵ and a lock-nut *b*⁶. 65

The set-screw *b*⁵ impinges upon the block *b*³ whenever the armature *b*² is in its normal position, and this is adapted to regulate the vertically-inclined position of the armature and to limit its return movement. The upper end of the supporting-frame *b* is provided with a projecting stud *c*, which forms the core for the solenoid *c* placed thereon. The upper extension of the armature *b*² is provided with an inner projecting insulated arm 70 *d*, which in its forward movement and when the armature *b*² is attracted to the magnet *c* comes in contact with one of the members of a spring-contact *f*. At the completion of the forward movement of the armature *b*² said 75 projecting arm *d* has separated the two members *f* and *f*¹ of the spring-contact *f*, and thereby broken any current which otherwise might have flowed through the same prior to the time that the magnet *c* has become energized. The upper extremity of the armature *b*² is provided with an automatically-adjustable 80

piston-contact plate *g*, which latter is designed to be brought in contact with a carbon block *h*, which is fastened to the insulating base-plate *a*³ by means of the collar *h*², the latter being provided also with a binding-post *h*³ in order to make the necessary electrical connection with other parts of the circuit. The contact-piston *g* is provided with 85 a shank *g*¹, which passes through a corresponding opening *g*² in the upper part of the armature *b*² and is provided also with a compression-spring *g*³, which normally rests within a suitable recess *g*⁴ of the armature *b*². 90 A binding-post *g*⁵ at the outer end of the shank *g*¹ provides means of electrical connections, such as conductors *i*, with one of the lugs *b*¹ of the main support *b*. For the purpose of obtaining the best results and easier 95 adjustment of all the moving parts and also 100

105

for the purpose of making a perfect contact between the outer face of the piston-plate g and the outer plate of the block h the shank g' , as well as the compression-spring g^3 , are designed to operate freely within the recess g^5 and the bore g^7 , through which the shank passes.

In the operation of my device and when applied to any electrical controlling apparatus, such as illustrated in Fig. 4, it becomes of considerable interest to the users of such devices to have the necessary work performed with as little waste of energy as possible to be effective and at the same time simple in construction. For this reason the armature b^2 is mounted so as to hold a vertical backwardly-inclined position when the circuit is open of the resistance, and it obtains such a position by reason of force of gravity without the expenditure of any other energy. As soon as the magnet becomes energized but little force is needed to attract the armature to a working or operative position and not until the armature-lever has been attracted close to the core of the magnet, and when the arm d has been brought to bear against the spring-contact f the armature is in its most effective position to finish its advancing motion, and thereby open the contact f . The piston-plate g at the same time has been brought to bear against the face of the carbon block h and makes and holds close contact therewith by means of the compression-spring g^3 , thereby insuring a perfect contact. As soon as the magnet is deenergized the compression-spring g^3 forces the armature b^2 backwardly, which when assuming its vertical position falls by force of gravity back to

its normal backwardly-inclined position. For the purpose of easy self-adjustment the piston-shank g' and the compression-spring g^3 move freely and easily in their bearings, as illustrated and described above. It will thus be seen that but little electrical energy is required to break the circuit by means of my invention and that it is simple and effective in all its movements.

Having fully described my invention, what I claim as new, and desire to secure by Letters Patent, is—

In a circuit-breaking device, a base-plate, spring-contact devices connected therewith, an armature-lever pivoted below said spring-contact devices and adapted to swing in a vertical plane and provided with an inwardly-directed arm adapted to operate in connection with said spring-contact devices means for limiting the outward movement of the armature-lever, a magnet placed between the support of the armature-lever and the spring-contact devices, a contact-block secured to the base-plate above the contact devices, and a spring-operated plate provided with a rod which passes through the end of the armature-lever and is adapted to operate in connection with said contact-block, said casing and the rod of the said spring-operated plate being provided with binding-posts.

In testimony that I claim the foregoing as my invention I have signed my name, in presence of the subscribing witnesses, this 13th day of February, 1906.

FREDERICK L. WILLARD.
